Primary Examiner — Michelle E. Wilson*Assistant Examiner* — Richard E Yenchesky(74) *Attorney, Agent, or Firm* — Warner Norcross + Judd LLP(57) **CLAIM**

The ornamental design for a brushroll for a floor cleaning apparatus, as shown and described.

DESCRIPTION

FIG. 1 is a front, right perspective view of a brushroll for a floor cleaning apparatus showing our new design;

FIG. 2 is a front, left perspective view thereof;

FIG. 3 is a top view thereof;

FIG. 4 is a front view thereof;

FIG. 5 is a right side view thereof; and,

FIG. 6 is a left side view thereof.

The details shown in broken lines form no part of the claimed design. In the figures, the brushroll for a floor cleaning apparatus is shown with a texture of small irregular lines that are provided to represent a microfiber material.

1 Claim, 4 Drawing Sheets(56)
